UNITED STATES PATENT OFFICE.

HAROLD WILLIAM NICHOLS, OF MAPLEWOOD, NEW JERSEY, ASSIGNOR TO WESTERN ELECTRIC COMPANY, INCORPORATED, OF NEW YORK, N. Y., A CORPORATION OF NEW YORK.

SELECTIVE CIRCUITS.

Application filed October 29, 1921. Serial No. 511,475.

To all whom it may concern:

Be it known that I, HAROLD WILLIAM NICHOLS, a citizen of the United States, residing at Maplewood, in the county of Essex, State of New Jersey, have invented certain new and useful Improvements in Selective Circuits, of which the following is a full, clear, concise, and exact description.

This invention relates to highly selective electric circuits.

One object of the invention is to selectively control the transmission of waves through a circuit.

Another object is to provide a method and means for sharply discriminating between waves to be transmitted through a circuit and waves to be excluded therefrom.

A further object of the invention is to prevent the flow of current of carrier or of other frequencies through the output circuit of an amplifier, modulator, detector, or other form of relay device, or similar apparatus.

It is old in the art to employ tuned circuits containing inductance and capacity to selectively transmit or suppress waves of certain frequencies in an electric circuit. Such tuned circuits are, in general, open to the objection that they only partially exclude undesired waves, and are thus subject to definite limitations. For example, the so-called antiresonant circuit consisting of a capacity reactance in shunt with an inductive reactance is, when the circuit contains appreciable resistance, only partially effective in preventing the flow therethrough of waves having the same period as the circuit.

In accordance with the present invention, a circuit is provided which completely blocks the flow of waves of one or more given frequencies and at the same time passes waves of other frequencies with any desired relative amplitude. It has been found that by properly proportioning the constants of a tuned circuit connected between the input and output circuits of a relay, waves of a period equal to that of the natural period of the tuned circuit may be completely or partially excluded from the output circuit of the relay.

The invention is specifically applied to a thermionic relay wherein the space current between the anode and cathode is controlled

by a grid connected to the input circuit. An equation, based upon the constants of the thermionic tube and the connected circuits, is employed to determine the values of the constants of the tuned circuit to be connected between the input and output circuits. By connecting several impedances, or a network, between the input and output circuits of a relay, waves of a plurality of frequencies may be selectively suppressed or controlled.

Features of the invention, believed to be novel, are pointed out in the appended claims. The following description taken in connection with the accompanying drawing specifies further objects and details of the invention.

Referring to the drawing, Fig. 1 is a schematic diagram showing a relay circuit arranged in accordance with this invention;

Fig. 2 is a circuit diagram showing the invention as applied to a signaling system;

Fig. 3 is a diagram showing the relation of currents in portions of the circuit of Fig. 2;

Fig. 4 is a circuit diagram showing the invention as applied to a carrier wave modulating system in which a component of some given frequency, such as the unmodulated carrier frequency, may be eliminated from the output circuit;

Fig. 5 is a circuit diagram showing a method of connecting a network or a plurality of tuned-impedances between the input and output circuits of a relay to limit the flow of waves of a plurality of frequencies;

Fig. 6 is a diagram showing variations of output current with frequency in a circuit such as that of Fig. 5.

Fig. 7 is a diagram of a modification of the modulator shown in Fig. 4, the modulating waves being impressed between the grid and anode.

In Fig. 1 the space discharge device, or relay tube 1 includes the cathode 2, the anode 3, and the control electrode or grid 4. The input circuit 5 includes the source of alternating potential e in series, between the cathode 2 and the grid 4. The output circuit 6 having the impedance Z_2 and the source of space current 7 included therein, is connected between the cathode 2 and the anode 3. The grid-anode circuit 8 containing

the impedance Z_3 , is connected between the input circuit 5 and the output circuit 6.

In an article by the inventor in the Physical Review, Lancaster, Pa., N. S. volume

5 XIII, 6, June 19, 1919, page 404, it is shown that a vacuum tube such as tube 1 when connected in a circuit such as shown in Fig. 1 may be considered as a virtual source of alternating electromotive force. However, in 10 Fig. 1 and in the other figures of the drawing, the system may be considered to have two alternating current generators connected in series through associated alternating current resistances. In Fig. 1, for example, 15 alternating current generator producing electromotive force E acts through impedance Z_3 , whereas tube 1 serving as a source of virtual alternating electromotive force acts through the internal alternating current resistances of tube 1. In addition, the 20 electromotive force of tube 1 is 180° out of phase with the electromotive force E . It has further been shown that an alternating current of a given frequency produced by 25 electromotive force E may be excluded from the output circuit 6 connected between the junction points, connecting one of these alternating current generators with its associated resistance to the other alternating 30 current generator. By tuning impedance Z_3 to resonance at the frequency which it is desired to exclude and by further adjusting the resistance of impedance Z_3 to a value 35 having the relation to the value of the alternating current resistance of tube 1 which will be explained more fully later, the variation in potential of this frequency at the junction points described may be prevented. When the resistance of impedance Z_3 is adjusted to the proper value and when impedance Z_3 is tuned to the frequency to be excluded, variations in the electromotive force E of this frequency will not produce any variations of this frequency in the current in 40 the circuit 6.

Any reactance which may exist between the plate and grid of the tube 1 may be compensated for in the tuning of impedance Z_3 so that the parallel paths comprising this 45 reactance and the impedance Z_3 will form a resonant circuit for the frequency to be excluded from the output circuit 6.

It has been found that the following equation applies to the circuit shown in Fig. 1, 50 where μ represents the amplifying constant of the tube 1; I , the current flowing in the output circuit 6 in response to the alternating potential e ; and R , the alternating current resistance between the cathode 2 and 55 the anode 3 in the tube 1;

$$I = \frac{e(\mu Z_3 - R)}{Z_2(R + Z_3) + Z_3 R} \quad (2)$$

By adjusting the resistance r , of the impedance Z_3 , at a frequency corresponding to

zero reactance of the impedance Z_3 , in accordance with the equation:

$$Z_3 = r = \frac{R}{\mu} \quad (2)$$

it will be seen that the numerator of the second member of the equation 1 becomes zero, or in other words the current I , in the output circuit of the repeater, will be zero for the frequency at which Z_3 is equal to r . If 75 r be adjusted to values other than in accordance with equation (2) above, the magnitude of the output current of the frequency at which Z_3 is of zero reactance, may be varied to any desired value.

A method for mathematically deriving and expressing the relation between elements of a circuit of this type, is outlined in an article by the inventor in the Physical Review, Lancaster, Pennsylvania, N. S. Vol. 35 XIII, No. 6, June, 1919, page 404.

It will be seen that the circuit of Fig. 1 employs a relay of the type which responds to impressed waves by varying the impedance of the tube element 1, connected between the terminals 2, 3 of the work circuit 6. In order to exclude current of a given frequency from the work circuit 6, a wave component of the given frequency is transmitted from the source e to the terminals 2, 3 of the work circuit, this wave component being of the same frequency and amplitude as the wave generated by relay action between the terminals 2, 3. Inasmuch as the wave transmitted from the source e is, with respect to the work circuit 6, 180° degrees out of phase with the wave of the same frequency generated in the relay, the two waves entirely neutralize each other with reference to the work circuit and are thus excluded therefrom. At frequencies other than the given frequency or frequencies to be excluded from the work circuit 6, the impedance Z_3 may be so great as to be in effect an open circuit, so that waves of 100 these frequencies are reproduced in the work circuit 6 without being neutralized by a wave component from the source e .

In Fig. 2 is shown one station of a duplex, or a multiplex system. The oscillator-modulator circuit 9, giving rise to modulated carrier waves, together with unmodulated carrier waves, is coupled to the input circuit 5 of the relay tube 1, the output circuit 6 of which is coupled to the conductor 10, which may be connected to an antenna as shown, or to a line wire or other transmission path. The relay 1 is preferably an amplifier. Between the input circuit 5 and the output circuit 6 is connected 115 the grid-anode circuit 8, containing the impedance 11, including the inductance 12, the resistance 13, and the capacity 14.

In order to prevent the flow through the circuit 6 of waves of some given frequency,

say the unmodulated carrier frequency component in a wave band f_1 , derived from the oscillator-modulator circuit 9, the impedance 11 is adjusted sharply to resonance with this frequency, and the resistance 13 is adjusted until the total effective resistance of the impedance 11 at this frequency is equal to the quotient of the alternating current resistance R of the tube, between the anode 10 and cathode divided by the amplification constant μ , in accordance with the equation (2) above.

Coupled to the conductor 10 is the input circuit 15 of the amplifying or detecting tube 16, the output circuit 17 of which is coupled to the receiving device 18. The grid-anode circuit 19 connected between the input circuit 15 and the output circuit 17 contains the impedance network Z_4 for preventing the flow through the circuit 17 of waves within the wave band f_1 , or other undesired bands. If only one frequency is to be suppressed the impedance Z_4 may be similar to the impedance 11, and will be tuned to resonance with the wave to be suppressed, while the resistance will be adjusted in accordance with the equation (2) above. In the case where several waves or a wave band is to be suppressed, the impedance may take the form described later in connection with Fig. 5.

The operation of the circuit shown in Fig. 2 is as follows: Carrier waves modulated in accordance with signals together with unmodulated carrier waves are impressed as a wave band f_1 by the oscillator-modulator 9, upon the input circuit 5 of the amplifier 1, which amplifies the waves to be transmitted and, in cooperation with the impedance 11, suppresses any undesired wave so that only the desired wave components are passed on to the output circuit 6 and the antenna from which the waves are radiated. At the same time waves of frequency f_2 from a distant station are being received by the antenna conductor 10, and are impressed upon the input circuit 15, amplified or detected by the tube 16, and transmitted to the receiving device 18. The impedance element Z_4 cooperates with the tube 16 to exclude from the output circuit 17, disturbing waves derived from the conductor 10, or any waves impressed upon the input circuit 15 which are not desired in the output circuit 17. Other circuits similar to circuit 9, 5, 1, 8, 6 and 15, 16, 19, 17, 18, may be coupled to the conductor 10, to provide more channels than in the duplex system shown, each channel being provided with impedances between the input and output circuits of the relay device to prevent the flow of undesired waves through the output circuits.

In Fig. 3, curve 20, 21, 22, designated as 65 I_6 , represents the alternating current flow-

ing in the output circuit 6 of Fig. 2, for different wave frequencies impressed upon the input circuit 5, while curve 23, 21, 24, indicated as I_{10} , represents the current flowing in the antenna conductor 10 over the same range of wave frequencies impressed upon the input circuit 5. Curve 25, indicated as I'_{10} , represents current which would flow in the antenna conductor 10 or other resonant circuit coupled to the output circuit 6, if the impedance 11 were not connected between the input circuit 5 and the output circuit 6. The impedance 11 may be very sharply tuned so that high selectivity is obtained, as indicated by the steep slope of the curve 23, 21, 24 between the maximum current points 23 and 24, and the point 21 corresponding to the frequency at which no current will flow in the antenna. The low impedance of the circuits 6 and 10 to currents having the frequencies corresponding to the point 23 and to the left thereof, and to the point 24 and to the right thereof, permits of the efficient transmission of desired side band frequencies or frequencies adjacent to that of the unmodulated carrier wave. The portion of curve I_{10} in the neighborhood of points 23, 24 as may be seen from the drawing is of such a shape that a band of wave frequencies such as a side band of modulated waves may be transmitted on either side of the frequency corresponding to the point 21 with very little or no distortion, whereas if the transmitted energy were attenuated in accordance with the antenna impedance characteristic alone as indicated by the curve I'_{10} , the distortion of the wave band would be considerable. In this respect the impedance 11 acts as a means to compensate for unequal attenuation of waves in some other portion of the system. The impedance 11, which may be of relatively small dimensions, is thus enabled to perform the same function as a more elaborate tuning means in the antenna circuit 10, and consumes a negligible quantity of energy as compared with that which would be consumed by circuit means inserted directly in the antenna circuit 10. Another advantage resulting from the use of the impedance 11 lies in the fact that the output circuit 6, and the antenna circuit 10 are of lower impedance and resistance than would be the case if wave suppressing means were inserted in circuit 6, or 10.

In Fig. 4, the source of modulating waves 26, together with the source of carrier waves 27 coupled to the input circuit 28 of the modulator tube 29, whose output circuit 30 is connected to the input circuit 28 by means of the impedance Z_5 which is adjusted to have negligible reactance to the frequencies to be eliminated, and to have a resistance as defined by equation (2) above. The output circuit 30 is connected to impress its varia-

4
tions upon the input circuit 31 of the amplifier 32, whose output circuit 33 is coupled to the antenna 10. Inasmuch as waves of unmodulated carrier wave frequency are suppressed before reaching the amplifier 32, the amplifier will be loaded only by energy which is to be utilized in the antenna circuit 10.

In Fig. 5 is shown the relay tube 34, the input circuit 35 of which is connected to the output circuit 36 by a network Z_6 including a resistance 37 having in series therewith a plurality of branch impedances 38, 39, 40, 41 etc., connected in parallel, each of these impedances comprising an inductance 42 in series with a capacity 43. The resistance 37 is adjusted together with the inductances 42, and the capacities 43, so that the reactance of any given circuit path traced between the input circuit 35 and the output circuit 36 is negligible for the frequencies of waves which are to be eliminated in accordance with equation (2) above.

Referring to Fig. 6, the curve 44, designated as I_{an} , represents the output current flowing in the circuit 36, Fig. 5, for different values of frequencies impressed upon the input circuit 35, the points 45, 46, 47, 48, etc., being the frequency values at which no current will flow in the output circuit 36, these frequencies being the frequencies at which paths of zero reactance are provided between the input circuit 35 and the output circuit 36. It is evident from the figure that a plurality of wave bands are substantially suppressed, the width of any one band being adjusted by varying the sharpness of tuning of the corresponding branch. By tuning the circuits 38, 39, 40, 41, etc., to frequencies which are closer together than that designated in Fig. 6, the effect of the various branches may be merged so that a band of frequencies may be more sharply suppressed than where a single series resonant circuit is employed.

In Fig. 7 a source of modulating waves 26 is coupled to the grid-anode circuit 49 of the modulator 29. Circuit 49 includes the impedance element 11 similar to that disclosed in connection with Fig. 2. The grid-anode circuit 49 between the input circuit 28 and the output circuit 30 is tuned to resonance with waves of carrier frequency derived from the source 27, while the resistance of said circuit may be adjusted in accordance with equation (2) above. Any type of load or receiving circuit may be associated with the output circuit 30 as, for example, the amplifier and antenna circuits shown in Fig. 4. If the resistance of the grid-anode circuit 49 be adjusted, at carrier frequency, in accordance with equation (2) above, waves of carrier frequency will be eliminated from the output circuit 30. By adjusting the resistance of the circuit 49 to

values different from that expressed in equation (2), any desirable amount of unmodulated carrier wave frequency may be transmitted or suppressed, for example, as the resistance of circuit 49 is increased above that defined by equation (2), the component of unmodulated carrier frequency becomes appreciable, and increases with further increases of resistance.

The principle of the invention has, for the purpose of clearness, been disclosed with particular reference to specific forms of circuits and relay or repeater devices, but the invention is not limited to any of these forms, it being understood that the term "relay device" as used herein covers any of the devices described in a generic sense. The appended claims more particularly point out the nature of the invention which it is desired to protect.

What is claimed is:

1. In an electric circuit, a relay device having input and output circuits, and means connected between said circuits to substantially completely prevent the flow of waves of a given frequency through said output circuit.

2. In an electric circuit, a relay device having input and output circuits, and an impedance element connected between said circuits to substantially completely prevent the flow of waves of given frequency through said output circuit.

3. In an electric circuit, a relay device having input and output circuits, an impedance element connected between said circuits to prevent the flow of waves of given frequency through said output circuit, the impedance of said element at said given frequency being equal to the impedance of said repeater divided by the amplification constant of said relay.

4. In an electric circuit, a relay device having input and output circuits, and an impedance element connected between said circuits to prevent the flow of waves of given frequency through said output circuit, the reactance of said element at said given frequency being zero.

5. In an electric circuit, a relay device having input and output circuits, an impedance element connected between said circuits to prevent the flow of waves of given frequency through said output circuit, said impedance being, in effect, a pure resistance at said given frequency.

6. In an electric circuit, a thermionic relay having an anode, a cathode, and a grid and means connected between said grid and anode to substantially completely prevent the flow of wave energy of a given frequency from said relay.

7. In an electric circuit, a thermionic relay having an anode, a cathode, and a grid, and an impedance element connected be-

tween said grid and anode to substantially completely prevent the flow of wave energy of a given frequency from said relay.

8. In an electric circuit, a thermionic relay having an anode, a cathode, and a grid, and an impedance element connected between said grid and anode to prevent the flow of wave energy of a given frequency from said relay, said element having an impedance at said given frequency which bears a predetermined ratio to the impedance of said relay.

9. In an electric circuit, a thermionic relay having an anode, a cathode, and a grid, and an impedance element including inductance, capacity, and resistance connected between said grid and anode to prevent the flow of wave energy of a given frequency from said relay, said resistance being adjusted to a value as given by the equation

$$r = \frac{R}{\mu}$$

10. In a relay circuit of the type which responds to impressed waves by varying the impedance of an element connected between the terminals of a work circuit containing a local source of energy, the method of excluding from said work circuit a first wave of given frequency and amplitude, which comprises impressing upon said terminals a second wave of the same frequency, and amplitude as said first wave, but 180 degrees out of phase therewith.

11. In a thermionic relay of the type including an anode, a cathode, and a grid, the method of reducing the effect of a given frequency component of E. M. F. produced between the anode and cathode, which comprises impressing an auxiliary E. M. F. across the anode and cathode.

12. In an electric circuit, a relay device having input and output circuits, and an impedance element including inductance, capacity and resistance connected between said circuits to prevent the flow of waves of a given frequency through said output circuit, said resistance being of a value as determined by equation (2).

13. In an electric circuit, a relay device having input and output circuits, and a network, having a plurality of natural periods, connected between said circuits to prevent the flow of a plurality of waves of given frequencies through said output circuit, said network including a resistance the value of which is determined by equation (2).

14. In a modulating system, a thermionic modulator having an anode, a cathode, and a grid, an input circuit connected to said grid and cathode, and an output circuit connected to said anode and cathode, a source of waves of carrier and modulating frequency in said input circuit, and means

connected between said input and output circuits to prevent the flow of unmodulated waves through said output circuit.

15. In a modulating system, a thermionic modulator having an anode, a cathode, and a grid, an input circuit connected to said grid and cathode, and an output circuit connected to said anode and cathode, a source of waves of carrier and modulating frequency in said input circuit, and an impedance element connected between said input and output circuits to prevent the flow of unmodulated waves through said output circuit.

16. In a modulating system, a thermionic modulator having an anode, a cathode, and a grid, an input circuit connected to said grid and cathode, and an output circuit connected to said anode and cathode, a source of waves of carrier and modulating frequency in said input circuit, an impedance element tuned to resonance with said carrier waves to prevent the flow of unmodulated waves through said output circuit.

17. In a modulating system, a thermionic modulator having an anode, a cathode, and a grid, an input circuit connected to said grid and cathode, and an output circuit connected to said anode and cathode, a source of waves of carrier and modulating frequency in said input circuit, an impedance element tuned to resonance with said carrier waves, the effective resistance of said impedance at carrier frequency being substantially equal to the resistance of said modulator between said anode and cathode divided by the amplification constant of said modulator.

18. In an electric signaling system, a common path for a plurality of signal currents, a relay coupled to said path, said relay having input and output circuits, and means connected between said input and output circuits to selectively prevent current of given frequency, flowing in said common path, from producing current in said output circuit.

19. In an electric signaling system, a common path for a plurality of signal currents, a relay coupled to said path, said relay having input and output circuits, a tuned circuit connected between said input and output circuits in series with a resistance having a value determined by equation (2) to selectively prevent current of given frequency, flowing in said common path, from producing current in said output circuit.

20. In an electric signaling system, a common path for a plurality of signal currents, a relay coupled to said path, said relay having input and output circuits, a tuned circuit connected between said input and output circuits to selectively prevent

6
current of given frequency, flowing in said common path, from producing current in said output circuit, said tuned circuit including inductance, capacity, and resistance, said resistance having a value determined by the equation

$$r = \frac{R}{\mu}$$

10 21. In an electric signaling system, a common path for a plurality of signal currents, a relay coupled to said path, said relay having input and output circuits, a tuned circuit connected between said input and output circuits to selectively prevent current of given frequency, flowing in said common path, from producing current in said output circuit, said tuned circuit containing inductance, capacity, and resistance, the impedance of said tuned circuit being equal at said given frequency to the impedance of said relay divided by the amplification constant of said relay.

15 22. In an electric signaling system, a transmission path carrying waves of given frequency, a source of waves of another given frequency coupled to said path to impress thereon waves of said other frequency, and receiving means coupled to said path, said receiving means including a relay having input and output circuits, and means connected between said input and output circuits to reduce the flow through said output circuit of waves of one of said given frequencies.

20 23. In an electric signaling system, a transmission path carrying waves of given frequency, a source of waves of another given frequency coupled to said path to impress thereon waves of said other frequency, and receiving means coupled to said path, said receiving means including a relay having input and output circuits, and an impedance element connected between said input and output circuits to prevent the flow through said output circuits of waves of one of said frequencies.

25 24. In combination, a space discharge device including anode, cathode, and control members, means for impressing a wave between two of said members, an output circuit connected between said anode and cathode, and means associated with said device for causing the absolute suppression of said waves from said output circuit.

30 25. In combination, a space discharge device including anode, cathode, and control members, means for impressing a wave between two of said members, an output circuit connected between said anode and cathode, and an impedance element associated with said device for causing the absolute suppression of said waves from said output circuit.

35 26. In a modulator system, a space discharge device including anode, cathode and control members, means for impressing a modulating wave between two of said members and a carrier wave between two of said members, an output circuit connected between said anode and cathode, and means associated with said device to suppress any desired amount of one of said impressed waves from said output circuit.

40 27. In a modulating system, a space discharge device including an anode, a cathode, and a control member, means for impressing a carrier wave upon said device, and means for impressing a wave solely between said control member and anode to modulate said carrier wave.

45 28. In a modulating system, a space discharge device including an anode, a cathode, and a control member, an output circuit connected between said anode and cathode, means for impressing a carrier wave upon said device, and means for impressing a wave solely between said control member and anode to modulate said carrier wave.

50 29. In an electric circuit, a relay device having input and output circuits, a load circuit associated with said output circuit having a frequency selective characteristic, and means connected between said input and output circuits to exclude energy of predetermined frequencies from said load circuit to compensate for the distortion produced by said load circuit.

55 30. In an electric circuit, a relay device having input and output circuits, a load circuit associated with said output circuit having a frequency selective characteristic, and an impedance connected between said input and output circuits to exclude energy of predetermined frequencies from said output circuit to compensate for the distortion produced by said load circuit.

60 31. In an electric circuit, a relay device having input and output circuits, a source of oscillations having a complex wave form impressed upon said input circuit, a load circuit associated with said output circuit having a frequency selective characteristic, and an impedance connected between said input and output circuits to compensate for the distortion produced by said load circuit, said impedance comprising series reactive elements tuned to one of the frequency components from said source, and a series resistance substantially equal to the internal resistance of said device divided by the amplification constant thereof.

65 In witness whereof, I hereunto subscribe my name this 27th day of October, A. D. 1921.

HAROLD WILLIAM NICHOLS.
